UNITED STATES PATENT OFFICE.

FREDERICK J. NASH, OF SOMERVILLE, MASSACHUSETTS, ASSIGNOR TO UNITED SHOE MACHINERY COMPANY, OF PATERSON, NEW JERSEY, A CORPORATION OF NEW JERSEY.

STOP MECHANISM.

1,093,588.

Specification of Letters Patent. Patented Apr. 14, 1914.

Application filed July 11, 1906. Serial No. 325,568.

To all whom it may concern:

Be it known that I, FREDERICK J. NASH, a citizen of the United States, residing at Somerville, in the county of Middlesex and 5 State of Massachusetts, have invented certain new and useful Improvements in Stop Mechanism; and I do hereby declare the following to be a full, clear, and exact description of the invention, such as will enable others skilled in the art to which it appertains to make and use the same.

The present mechanism relates to improvements in stop mechanism.

The object of the invention is to improve 15 the construction and operation of stop mechanism, more particularly of stop mechanism of the type which, when applied to a sole rounding machine, is adapted to allow the table of the machine to continue to rotate 20 for a short distance, owing to the momentum of the various operating parts of the machine, after it has made a complete rotation and has been disconnected from the source of power, and to then return the 25 table to its normal starting point. In this aspect the invention is an improvement upon the stop mechanism disclosed in the pending application of Benjamin F. Mayo, filed November 7, 1902, Serial No. 130,385, to 30 which reference is made by permission, the object of the invention being to improve the operation of the mechanism disclosed in said application by the introduction of checking devices to prevent jar and cause the mechanism to operate gradually and easily.

Other objects of the invention will be noted in connection with the description of the illustrated embodiment.

A stop mechanism embodying a preferred 40 form of the invention is illustrated in the accompanying drawings as applied to a sole rounding machine of a type well known in the art.

In the drawings Figure 1 is a plan view 45 of the stop mechanism; Fig. 2 is a vertical section of the same; Fig. 3 is a sectional detail view showing the operating lever and connected mechanism; Fig. 4 is a detail view of the driving pinion and its friction disk; 50 Fig. 5 is a detail view of the pinion driver and its friction disk; Fig. 6 is a detail view of the air-check connected with the operating lever; and Fig. 7 is a detail sectional view of the same showing the adjustable air 55 vent.

The table 1 of the sole rounding machine to which the stop mechanism is applied, is driven by a driving shaft 2 rotated by a pulley 3 connected with a suitable source of power, and between the pulley and the table 60 is introduced the stop mechanism of the present invention, for the purpose of starting, stopping and controlling the actuation of the table by the pulley. The table 1 is provided with an annular bevel gear 4 meshing with a pinion 5 which is loosely mounted on the inner end of the shaft 2. The bevel gear 5 is connected with the driving shaft so as to transmit a movement of the latter to the table, the connection being such 65 that the gear is allowed to rotate through a part of a revolution after the driving shaft is brought to rest, and is then returned to its normal position with relation to the shaft. This operation is for a purpose well 70 understood in connection with sole rounding machines, and is accomplished in the present device by means similar to those disclosed in the application above referred to, the bevel pinion 5 being loosely mounted 75 upon the shaft and connected therewith by means of a driver 6 fixed to the shaft and provided with a projection 7 which engages a corresponding lug 8 on the pinion. A spring 9 connects the driver 6 and the pinion, and tends normally to hold the lug 8 and the projection 7 in contact, and during the rotation of the table by the driving shaft, the pinion and the table are driven 80 positively by such engagement. When the 90 shaft is stopped, however, the pinion continues to turn through a part of a rotation, the lug 8 being disconnected from the projection 7, and it is then returned again by the spring 9. The projection 7 is provided 95 with a mechanism 10 to prevent jar between the lug and the projection, and in the present invention the operation of this part of the mechanism is further improved by the interposition between the driving shaft and 100 the pinion of a checking device comprising two spring-pressed friction surfaces. As shown in Figs. 2 and 4, the pinion is provided with a recess in which is located a friction disk 11. The friction disk is notched at two points so as to engage ribs 12 on the pinion to prevent relative rotation of the pinion and disk. A coöperating disk 13 is secured to the end of the shaft by a screw 14 and caused to rotate with the shaft 105 110.

or to remain fixed therewith by a pin 15. Compression springs 16 located in sockets in the pinion maintain the disks in frictional engagement, so that they tend to check relative movement of the pinion and the shaft. 5 This device tends to retard the relative movement of the pinion and the shaft to such an extent as to prevent jar when the table is finally brought to rest, either at the 10 end of its forward rotation or upon its return movement, and thus noise and wear upon the parts are diminished.

The means for connecting and disconnecting the pulley 3 and the shaft 2 and for 15 stopping the rotation of the shaft when so disconnected, are similar in general to those shown in the application above referred to. The pulley is loosely mounted upon a sleeve 17, which in turn is loosely mounted upon 20 the hub 18 of a wheel or disk 19 secured to the shaft. The pulley and the wheel 19 are provided with conical clutch members 20 by which the rotation of the pulley is transmitted to the wheel and to the driving shaft. 25 The sleeve 17 is mounted to move longitudinally of the shaft, and the pulley is caused to move with it by means of a flange 21 on the sleeve, which bears against one end of the hub of the pulley, and by means 30 of a flange on a block 22 mounted to slide longitudinally on the shaft, this flange bearing against the other end of the hub of the pulley and against the end of the sleeve 17. A coiled spring 23 tends constantly to move 35 the block 22 along the shaft so as to push the pulley to the left and bring the clutch members on the pulley and the wheel 19 into engagement.

In order to disengage the clutch members 40 and stop the rotation of the driving shaft, spring-actuated mechanism is provided which is held out of operation by means of a latch and is thrown into operation by a trip actuated from the table 1. Mounted in 45 a recess in the hub of the wheel 19 are two disks 24 and 25, both free to move longitudinally on the shaft. The disk 24 is provided with two pins 26 which pass through holes in the wheel 19 and engage the flange 50 21 on the sleeve 17. The operating lever 27 by which the operation of the stop mechanism is primarily controlled, is pivotally mounted upon a bushing 29 forming a bearing for the driving shaft and mounted in 55 the portion 30 of the frame of the machine, in which the stop mechanism is mounted. In the hub of the operating lever two pins 31 are loosely mounted at diametrically opposite sides of the driving shaft. These 60 pins bear at one end against cam surfaces on a collar 32 clamped upon the bushing 29, and at their other ends they bear against the disk 25. This arrangement is such that a movement of the operating lever in one 65 direction forces the pins against the disk 25

and moves the disks 24 and 25 in a direction to actuate the sleeve 17 to disconnect the clutch members on the pulley and the wheel 19 so as to stop the rotation of the shaft while a return movement of the lever allows 70 the spring 23 to move the sleeve back and again connect the clutch members.

The wheel 19 is provided with a braking member 33 with which two brake shoes 34 are arranged to coöperate to arrest the rotation of the driving shaft when the clutch members are disengaged. The brake shoes are secured to arms 35 pivotally mounted at 75 36 on opposite sides of the driving shaft and are connected by links 37 with the hub of the operating lever, the arrangement being such that the brake shoes are brought into contact with the braking member 33 when the operating lever is moved in a direction to disengage the clutch members. Such movement of the operating lever is caused by a spring 38 connected by means of a link 39 with the rear end of the operating lever. The lever is held during the operation of the machine in the position to which it is moved 80 to permit the clutch members to engage and to hold the brake shoes out of contact with the braking member by means of a latch 40 pivotally mounted upon the lever and engaging a fixed stop 41. To release the lever 85 the latch 40 is actuated by means of a trip 42 carried by the table 1, this trip being so located upon the table that as the latter completes its rotation the trip engages the end of a lever 43 secured to a stem 44 journaled in the frame of the machine. An arm 45 projects laterally from the lower end of the stem 44 and contacts with the latch 40 when the lever 43 is actuated by the trip so as to disengage the latch from the stop 41. When 90 the latch is so disengaged, the spring 38 moves the operating lever so as to disconnect the clutch members and apply the brake. 95

A cylinder 46 is mounted upon the frame 110 member 30 and is provided with a piston 47 connected by means of a pitman 48 with the rear end of the operating lever. The lower end of the cylinder 46 is provided with a vent 49 adjustable by means of a screw 115 plunger 50. This device constitutes a pneumatic check. When the latch 40 is released and the spring 38 operates to draw the end of the operating lever down, the air-check operates to retard such movement, the extent of such retarding effect being gaged by the adjustment of the vent 49, and thus the movement of the operating lever in applying the brake shoes is gradual. 120

Although of particular value in connection with the stop mechanism of the type above described, the present invention is applicable to stop mechanisms of other kinds, and the invention in general is not limited to the details of construction and operation of 125 130

the illustrated embodiment, but may be embodied in other forms particularly defined in the claims.

Having now described the invention, what is claimed is:

- 5 1. A stop mechanism having, in combination, a shaft, means for actuating said shaft, means for connecting and disconnecting said shaft and its actuating means and stopping said shaft, mechanism driven by said shaft, a spring connection between the shaft and said mechanism arranged to allow an independent forward movement of the mechanism and to impart a return movement thereto after said shaft is stopped, and means for retarding said independent forward movement, substantially as described.
- 10 2. A stop mechanism having, in combination, a shaft, means for actuating said shaft, means for connecting and disconnecting said shaft and its actuating means and stopping said shaft, mechanism driven by said shaft, a spring connection between the shaft and said mechanism arranged to allow an independent forward movement of the mechanism and to impart a return movement thereto after said shaft is stopped, and means for retarding said independent forward movement, substantially as described.
- 15 3. A stop mechanism having, in combination, a shaft, a gear driven by the shaft, means for imparting a positive forward movement to the gear from the shaft, a spring connection between the shaft and the gear arranged to allow an independent forward movement of the gear and to impart a return movement thereto, and a retarding device for checking such relative movements of the shaft and gear, substantially as described.
- 20 4. A stop mechanism having, in combination, a shaft, mechanism driven by the shaft, means for actuating the shaft, means for stopping the shaft, a spring connection between the shaft and said mechanism arranged to allow an independent forward movement of said mechanism and to impart a return movement thereto after said shaft is stopped, and a retarding device for checking such return movement, substantially as described.
- 25 5. A stop mechanism having, in combination, a shaft, mechanism driven by the shaft, means for actuating the shaft, means for stopping the shaft, a spring connection between the shaft and said mechanism arranged to allow an independent forward movement of said mechanism and to impart a return movement thereto after said shaft is stopped, and a retarding device for checking such return movement, substantially as described.
- 30 6. A stop mechanism having, in combination, a shaft, a gear driven by the shaft, means for imparting a positive forward movement to the gear from the shaft, a spring connection between the shaft and the gear arranged to allow an independent forward movement of the gear and to impart a return movement thereto, and two spring-pressed friction members rotating respectively with the shaft and the gear and operating to check relative rotation of the shaft and gear, substantially as described.
- 35 7. In testimony whereof I affix my signature, in presence of two witnesses.
- 40 8. FREDERICK J. NASH.
